UNITED STATES PATENT OFFICE.

JESSE W. NICHOLS, OF CHICAGO, ILLINOIS.

PAIL.

No. 863,627.

Specification of Letters Patent.

Patented Aug. 20, 1907.

Application filed January 26, 1903. Serial No. 140,591.

To all whom it may concern:

Be it known that I, JESSE W. NICHOLS, a citizen of the United States, residing at Chicago, in the county of Cook and State of Illinois, have invented certain new 5 and useful Improvements in Pails, of which the following is a specification.

My invention relates to sheet-metal pails or buckets, having reference more particularly to the tin pails extensively used in packing lard, cottolene, and like 10 products for retail distribution, although my invention is capable of useful application to pails and buckets of other kinds and for other purposes.

Most tin lard pails at present in use have soldered on their outer surface at diametrically-opposite points 15 near the upper end of the pail-body a pair of hollow ears centrally apertured for the reception of the inwardly-turned or hooked ends of the bail, the purpose thereof being to preserve imperforate and intact the containing walls of the pail against leakage of the 20 contents at the points where the bail is pivoted to the body, or the introduction of dirt and other objectionable foreign matter at such points.

My invention has for its principal object to simplify and cheapen the construction of such pails through the 25 provision of a novel construction of pail-ear which dispenses entirely with the use of solder, at the same time presenting a stronger construction and one equally efficient in preserving the contents of the pail from leakage or injury.

30 To this end my invention consists in a pail-body provided with a non-soldered bail-receiving ear having the peculiarities of construction and form and conjunction of parts substantially as hereinafter described and pointed out in the claims.

35 In the accompanying drawings I have illustrated a preferred embodiment of my invention, and referring thereto—Figure 1 is a side elevation of a tin pail equipped with my improved pail-ear for uniting the bail to the body of the pail; Fig. 2 is a detail fragmentary view of the inner surface of the body of the pail at and adjacent to the ear; Fig. 3 is a transverse section on the line 3—3 of Fig. 2; and Figs. 4 and 5 are detail perspective views of the coöperating elements of my two-part pail-ear.

40 Considering the drawings in detail, A designates the body of the pail in the form of the ordinary tin lard pail, and B the cover thereof also in the usual form.

C is the usual stiff wire bail, the lower ends of which are inwardly-turned or hooked to engage the pail-ears.

50 In accordance with my invention the body A of the pail is provided on its opposite sides at the diametrically-opposite points where the pail-ears are usually attached with a pair of countersunk circular openings, the disks of metal actually removed to form such openings being of smaller diameter than the diameter of the completed openings, whereby a certain annular portion

of the metal immediately surrounding the cut-out hole is punched and stamped inwardly, thereby forming a countersunk annular seat, indicated at a, and an inwardly-projecting flange shown at a'. The ear proper 60 designed to be seated in and completely and tightly fill said opening is a two-part ear, composed of a pair of stamped sheet-metal members shown separately in detail at D and E in Figs. 4 and 5 respectively. The member D is formed up in the inverted hat-shape 65 shown from a flat sheet-metal disk by a suitable punch or die, and has a short cylindrical body d, closed by a head d', and surrounded by a marginal flange d², all of said parts of course being integral. The cylindrical body d is made of a size to tightly fit within the flange 70 a', and the flange d² is of a size to snugly fit the countersunk seat a, with the outer face of the flange just flush with the surrounding outer surface of the pail-body. The member E is similarly shaped up from a circular disk of sheet-metal into the form shown in Fig. 5, 75 whereby it has a short cylindrical body e and an integral head e', which latter has a central perforation e² of a size to admit the hooked end of the bail C. The cylindrical body e of this member is of a diameter to tightly telescope within the cylindrical body d of the 80 member D.

In assembling the parts of the ear and seating the latter in the body of the pail, the members D and E are first telescoped with their concaved faces opposed to each other, thereby forming a hollow body having a 85 completely closed inner end, and the only opening to the interior of which is the bail-hole e² in the outer face thereof. This hollow body thus formed is then driven into the countersunk and flanged circular opening in the wall of the pail-body, completely filling and tightly 90 closing the latter; and it is locked therein against accidental displacement by locking lugs which may be conveniently formed by punch-pricking the inner margin of the ear over the inner edge of the flange a', as indicated at f. The inwardly-bent ends of the bail C are then 95 inserted in the apertures e², and the pail is complete.

Among the advantages possessed by my invention over the ordinary soldered pail-ear I may mention the dispensing with the use of solder, which is expensive and not always reliable as a uniting agent; the fact 100 that the parts of my pail-ear can be quickly and cheaply stamped and assembled, requiring no special tools or processes in their formation; the fact that the ear thus applied lies almost wholly within the wall of the pail, thus avoiding the unsightly appearance produced by 105 ears which are merely attached to and project outwardly from the outer surface of the pail; and the fact that the ear thus formed possesses great strength being inseparable from the pail-body by any ordinary or even unusual strain on the bail. It will also be obvious that 110 the ear may be seated so snugly in the flanged receiving aperture of the body as to be no less effective to prevent

leakage and exclude dirt than any imperforate portion of the wall of the pail. My improved pail-ear is also cheaper to make and apply than the soldered ear, aside from its superior efficiency in service.

5 I-claim:

1. A pail-body having openings at opposite points formed through its side walls and inwardly extending flanges surrounding said openings, in combination with two-part bail ears, each comprising a pair of interfitting 15 inversely disposed stamped metal concave members, the outer of which has a flange fitting the countersink of the opening and punch-pricked locking lugs overlying the edge of the flange of the opening, and the inner of which has a central hole to receive the bail-hook, substantially as described.
- 10 2. A pail-body having countersunk openings at opposite

points formed through its side walls and inwardly extending flanges surrounding said openings, in combination with two-part bail ears, each comprising a pair of interfitting 15 inversely disposed stamped metal concave members, the outer of which has a flange fitting the countersink of the opening and punch-pricked locking lugs overlying the edge of the flange of the opening, and the inner of which has a central hole to receive the bail-hook, substantially as described. 20

JESSE W. NICHOLS.
